Application July 21, 1945, Serial No. 606,320

6 Claims. (Cl. 89—140)

1

The present invention relates to improvements in self-loading firearms and relates more particularly to self-loading firearms of the type which may be selectively utilized either as full-automatic or as semiautomatic weapons, i. e., weapons which will either automatically reload and repeatedly discharge as long as the trigger is held in its "pulled" position, or which will automatically reload but require the normal operation of the trigger to effect the discharge of each shot.

One of the main objects of the present invention is to provide a superior self-loading firearm of the type which may be utilized either as a full-automatic or a semiautomatic firearm and which will combine reliability of functioning with economy of manufacture and ease of maintenance.

Another object of the present invention is to provide a superior self-loading firearm of the type above referred to, having a simple, reliable and effective arrangement of parts whereby the firearm may be readily converted from semiautomatic to full-automatic operation and vice versa.

A further object of the present invention is to provide an automatic self-loading firearm having a superior construction and arrangement of parts whereby the rate of fire may be kept at a relatively-low rate as is sometimes desired to meet certain requirements.

A still further object of the present invention is to provide a superior full-automatic firearm having a construction and arrangement of parts whereby a wide range of rates of fire may be provided for without requiring the re-designing of the weapon.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a broken view in side elevation of the portion of a firearm-structure adjacent the receiver and with the stock omitted, the parts being shown in the positions which they assume at the instant of discharge and when the adjustment is made for full automatic fire;

Fig. 2 is a broken view partly in side elevation and partly in the vertical central longitudinal section of the portion of the firearm located immediately forwardly of the portion illustrated in Fig. 1;

Fig. 3 is a top or plan view of the portion of the firearm shown in Fig. 1 and with the rear portion of the action-slide shown in horizontal section;

Fig. 4 is a broken view of the left side of the

2

rear portion of the firearm-structure but on a smaller scale than the preceding figures;

Fig. 5 is an underside view of the showing of Fig. 4 but with the trigger-plate unit omitted and with the parts shown in the positions which they assume as the action-slide is moving forwardly following the discharge of the firearm and with the timing-bar about to be disengaged from the action-slide;

Fig. 6 is a similar view but showing the timing bar after its release and at the limit of its rearward travel and at the instant of the discharge of the firearm;

Fig. 7 is a view similar to Figs. 5 and 6 but showing the action-slide retired to the limit of its rearward movement immediately following the discharge of the firearm as a result of the action illustrated in Fig. 6;

Fig. 8 is a broken view in vertical central-longitudinal section of the rear portion of the firearm-structure and showing the trigger held in its pulled position and the hammer as held in its cocked position by the secondary-sear;

Fig. 9 is a view in rear elevation of the showing of Fig. 8;

Fig. 10 is a perspective view of the selector-lever, detached;

Fig. 11 is a similar view of the sear-actuating lever;

Fig. 12 is a perspective view of the timing-bar, detached;

Fig. 13 is an underside view similar to Fig. 6, but showing the forward end of the timing-bar swung into its retired position to thereby convert the firearm for semiautomatic fire; and

Fig. 14 is a broken detail sectional view through the left side-wall of the receiver and through the timing-bar and timing-spring, taken on the line 14—14 of Fig. 4.

The particular gas-operated self-loading firearm illustrated in the accompanying drawings and chosen for purposes of making clear one form of the present invention, includes in the main, a receiver 15, a barrel 16, a trigger-plate unit 17, a breech-bolt 18 and an action-slide 19.

The breech-bolt 18 above referred to is mounted in the receiver 15 with capacity for both longitudinal reciprocation and lateral oscillation. The said breech-bolt is formed adjacent its forward end with two locking-lugs 20 and 21 respectively offsetting from the breech-bolt in substantially diametrically-opposite directions. The left side-wall 22 of the receiver 15 is formed with a forwardly-facing locking-abutment 23 which is adapted to be engaged by the rear face of the locking-lug 20 of the breech-bolt 18. Similarly, the right side-wall 24 is formed with a forwardly-facing locking-abutment 25 which is adapted to be engaged by the rear face of the locking-lug 21 of the breech-bolt 18.

Extending radially outwardly from and formed integral with the outer end of the locking-lug 24 of the breech-bolt 18 is an operating-lug 26 which extends into a cam-recess 27 formed in the inner face of the rear portion 28 of the action-slide 19 before referred to, at a point adjacent the outwardly-projecting handle 29 of the said action-slide.

The cam-recess 27 and the operating-lug 26, as well as other features of the breech-bolt 18, correspond generally to similar features embodied in the well-known Garand military rifle and in the M1 carbine. It is sufficient to here note that the surfaces of the cam-recess 27 contact with the surfaces of the operating-lug 26 in such manner that when the action-slide 19 is moved rearwardly, the breech-bolt 18 will first be caused to turn in a clockwise direction (as viewed from the front) to disengage the locking-lugs 20 and 21 respectively from the locking-abutments 23 and 25 of the receiver 15. Following this unlocking movement of the breech-bolt, the coaction of the surfaces of the cam-recess 27 with the operating-lug 26 will then effect the direct rearward axial movement of the breech-bolt 18. Conversely, when the action-slide 19 is moved forwardly (following the above-described rearward movement thereof), the coaction of the surfaces of the cam-recess 27 with the operating-lug 26 will first draw the breech-bolt 18 forwardly until such time as the respective rear faces of the locking-lugs 20 and 21 thereof register with the locking-abutments 23 and 25 of the receiver 15, whereupon the breech-bolt will be turned transversely in a counterclockwise direction to again lock the breech-bolt in its breech-closing position.

The action-slide 19 above referred to includes a relatively-slender bar-portion 30 formed integral with and extending longitudinally of the firearm structure between the rear portion 28 thereof and a crosshead 31 at the extreme forward end of the action-slide. The said bar-portion 30 constitutes the major portion of the length of the action-slide 19 and reciprocates longitudinally along the right side of the receiver 15 and the barrel 16.

The crosshead 31 above referred to extends beneath the barrel 16 and has its forward face normally engaged with the rear face of the stem 32 at the rear of a piston generally designated by the reference character 33, as is especially well shown in Fig. 2. The said piston also includes a relatively-large-diaetered head 34 located at the forward end of the piston and reciprocating in a rearwardly-opening piston-chamber 35. The piston-chamber 35 just referred to is formed in a cylinder-lug 36 formed integral with and depending from the barrel 16 at a point slightly forward of the front end of the receiver 15. The stem 32 of the piston 33 extends rearwardly through a ring-like stop-member 37 which is threaded into the rear end of the piston-chamber 35 and which is adapted to have its forward face engaged by the rear face of the head 34 to limit the rearward travel of the piston 33 as a whole.

Extending forwardly and upwardly from the front end of the piston-chamber 35 is an inclined gas-passage 38 which intersects the bore 39 of the barrel 16, as is shown particularly well in Fig. 2.

For the purpose of yieldingly holding the action-slide 19 in its forward position and hence also serving to hold the breech-bolt 18 in its

forward or breech-closing position, a helical breech-closing spring 40 is employed. The said breech-closing spring has its rear portion located in a longitudinal spring-passage 41 formed in the lower portion of the right side-wall 24 of the receiver 15, as is shown in Fig. 1. The rear end of the breech-closing spring 40 thrusts rearwardly against a plunger 42 mounted for reciprocation in the rear end of the spring-passage 41. The rear end of the said plunger 42 bears against the right arm 43 of a sear-actuating lever generally designated by the reference character 44, as is especially well shown in Figs. 5, 6 and 7. The said sear-actuating lever is of substantially-U-shaped form and includes a left arm 45 which is longer than the right arm 43, as is especially well shown in Fig. 11. On its outer edge, the left arm 45 is formed with an L-shaped retaining-finger 46 having its upper end inwardly directed and entered into a retaining-groove 47 formed in the left side-wall 22 of the receiver 15 adjacent the lower edge of its rear portion, as is illustrated in Fig. 9.

The major portion of the sear-actuating lever 44 is located adjacent the under face of the rear portion of the receiver 15, and is mounted in the location referred to for pivotal movement by means of a pivot-pin 48 extending upwardly into the adjacent portion of the right side-wall 24. The tension of the breech-closing spring 40 applied against the forward face of the right arm 43 of the sear-actuating lever 44 serves to normally hold the latter in the position in which it is shown in Figs. 5 and 7 in which the forward face of the left arm 45 is in engagement with a rearwardly-facing stop-abutment 49 formed on the left side-wall 22 of the receiver 15 adjacent the rear end thereof, as is especially well shown in Fig. 4.

At its central portion, the sear-actuating lever 44 above referred to is formed with a downwardly-extending finger 50 which is adapted to engage with the upper end of a secondary sear 51 as shown in Fig. 8, to swing the said secondary-sear rearwardly under circumstances as will more fully hereinafter appear.

The said secondary-sear 51 fits into a central longitudinal recess 52 formed in the upper portion of a trigger generally designated by the reference character 53. Both the said secondary-sear 51 and the said trigger 53 are mounted for pivotal movement upon a pivot-pin 54 extending transversely across a recess 55 in the rear portion of the trigger-plate unit 17, as is especially well shown in Fig. 8.

The secondary-sear 51 above referred to has an upwardly-extending arm 56 and is urged in a direction required to swing the said arm forwardly by means of a helical sear-spring 57. The said sear-spring is mounted in an upwardly-opening spring-pocket 58 formed in the rear portion of the trigger 53 and opening upwardly into the bottom of the recess 52 in the latter, as is particularly well shown in Fig. 8. The upper end of the sear-spring 57 thrusts upwardly upon the rear portion of the secondary-sear 51.

On its forward upper portion, the arm 56 of the secondary-sear 51 is provided with a downwardly-facing cocking-abutment 59 which is adapted to releasably engage an upwardly-facing cocking-abutment 60 formed at the rear of an offsetting-arm 61 integral with and rearwardly projecting from the upper portion of a hammer generally designated by the reference character 62. The said hammer has its lower end extended

into the forward portion of the recess 55 in the trigger-plate unit 47 and pivotally mounted therein by means of a transverse hammer-pin 63. The forward upper portion of the hammer 62 is adapted to strike and drive forwardly a firing-plunger 64 mounted for reciprocation in an axial direction in the breech-bolt 18. The rear end of the said firing-plunger normally projects slightly beyond the rear end of the breech-bolt 18, and when driven forwardly by the hammer 62 as described, the said firing-plunger effects the discharge of the firearm in a manner well known in the art.

On its forward lower portion opposite its cocking-abutment 60, the arm 61 of the hammer 62 is provided with an upwardly-facing cocking-abutment 65 which is adapted to engage with a downwardly-facing cocking-abutment 66 formed at the upper end of a sear-arm 67 projecting upwardly from the forward portion of the trigger 53 before referred to, as will be apparent by reference to Fig. 8 in particular.

The trigger 53 is yieldingly urged to turn about the pivot-pin 55 as a center in such direction as to swing its finger-piece forwardly and to swing its sear-arm 67 rearwardly, by means of a helical trigger-spring 68. The upper portion of the said trigger-spring is accommodated in a shallow downwardly-opening spring-pocket 69 formed in the forward under portion of the trigger 53, while the lower end of the said spring engages with an adjacent upwardly-facing surface of the trigger-plate unit 47.

The upper portion of the hammer 62 above referred to is urged to swing forwardly by means of a helical hammer-spring 70, which action is releasably restrained by the cocking-abutments 59 or 66 respectively of the secondary-sear 51 and the trigger 53, all in a manner as will more fully hereinafter appear.

In the lower portion of its left side-wall 22, the receiver 15 is formed with a longitudinal T-shaped guide-groove 71 opening through the outer face of the said side-wall. At its forward end, the guide-groove 71 intersects the forward end of the receiver and at its rear end intersects the stop-abutment 49 at the rear of the receiver and with which the left arm 45 of the sear-actuating lever 44 normally engages. Mounted for lengthwise reciprocation in the guide-groove 71 is the rear portion of what, for convenience of description, may be designated as a "timing-bar" 72. At its rear end, the timing-bar 72 is formed with an upwardly-extending retaining-finger 73 and a vertically-aligned downwardly-extending retaining-finger 74 respectively extending into the upper and the lower undercut portions of the guide-groove 71 in the receiver 15. The said timing-bar is also formed with a second downwardly-extending retaining-finger 75 which extends into the lower undercut portion of the guide-groove 71 and, in a sense, acts as a fulcrum-point, in a manner as will hereinafter appear, as well as discharging the function, jointly with the retaining-fingers 73 and 74, of retaining the timing-bar 72 against outward lateral displacement from the guide-groove 71.

Mounted in the upper undercut portion of the guide-groove 71 in the receiver 15 is a helical timing-spring 76 which thrusts at its rear end against the forward face of the upwardly-extending retaining-finger 73 of the timing-bar 72 and which thrusts at its forward end against the cylindrically-contoured stem 77 of a selector-lever generally designated by the reference char-

acter 78, as is especially well shown in Figs. 4 and 14.

The selector-lever 78 above referred to includes, in addition to its stem 77, a radially-offsetting finger-piece 79, as is especially well shown in Fig. 10. The said finger-piece 79 rests against the upper surface of the forward portion of the left side-wall 22 of the receiver 15, while the stem 77 thereof extends downwardly into a cylindrically-contoured socket 80 also formed in the said left side-wall 22 and extending downwardly to a point adjacent the extreme lower limit of the longitudinal guide-groove 71, as is shown in Fig. 4.

At its lower end, the stem 77 of the selector-lever 78 is formed with a downwardly-extending eccentric-finger 81 which is adapted in a manner as will hereinafter appear, to engage with the inner face of the adjacent portion of the timing-bar 72 to outwardly flex the forward portion thereof, as illustrated in Fig. 13 and for purposes as will more fully hereinafter appear. As indicated in the Figs. 3 and 4, the upper portion of the stem 77 is engaged by a detent-plunger 82 mounted for reciprocation in the left side-wall 22 and urged forwardly into engagement with the stem 77 by a helical detent-spring 83. The function of the said detent-plunger 82 is to yieldingly hold the selector-lever 78 in either of its two rotational positions, as will be hereinafter described.

At its forward end, the timing-bar 72 is formed with an inwardly-projecting hook generally designated by the reference character 84 and including a forwardly-and-outwardly-inclined releasing surface 85 and a rearwardly-facing latching-abutment 86. The latching-abutment 86 just referred to is adapted to engage with the forward face of the left side of the crosshead 31 of the action-slide 19, as is illustrated in Fig. 5. The sloping releasing-surface 85 of the hook 84 of the timing-bar 72 is adapted on occasion, to engage with a forwardly-and-outwardly-sloping releasing-surface 87 formed on the left rear corner of the cylinder-lug 36, as is especially well shown in Fig. 5 and for purposes as will hereinafter appear.

From the foregoing it will be observed that the timing-spring 76 constantly urges the timing-bar 72 rearwardly, to thus engage the rear end of the latter with the forward face of the left arm 45 of the sear-actuating lever 44. It is to be further noted that the effective force of the said timing-spring on the lever 44 is materially less than the effect of the breech-closing spring 40, despite the fact that the latter spring acts on the lever 44 at a point closer to its pivot-point than does the timing-spring 76. Thus, under ordinary conditions, the breech-closing spring 40 has sufficient thrust to normally hold the sear-actuating lever 44 in such position that its left arm 45 is against the stop-abutment 49 of the left side-wall 22 and against the rear end of the timing-bar 72, despite the tension of the timing-spring 76.

Full-automatic operation.

For purposes of description, let it be assumed that the marksman wishes to have the firearm function as a full-automatic firearm, i. e., continue to discharge the contents of a magazine as long as the trigger 53 is held in its "pulled" position.

Under the conditions above referred to, the marksman will swing the selector-lever 78 so that its finger-piece 79 is directed forwardly as is shown by full-lines in Figs. 1, 3 and 4 to thereby swing its eccentric-finger 81 into its innermost

position. This movement of the said finger will permit the forward portion of the timing-bar 72 to spring into its inward position, as is shown especially well in Figs. 5, 6 and 7.

It may further be assumed that the firearm has just discharged a cartridge located in the rear end of the bore 39 of the barrel 16.

Now under the circumstances above described, gases from the just-fired cartridge will pass downwardly through the gas-passage 38 in the cylinder-lug 36 and will impinge against the forward face of the head 34 of the piston 33. The impingement of gases just referred to will drive the said piston rearwardly until the rear face of its head 34 engages with the forward face of the ring-like stop-member 37. The relatively-short rearward movement of the piston 33 will be sufficiently violent to cause the stem 32 of the said piston to drive the entire action-slide 19 rearwardly against the tension of the breech-closing spring 40 from the position in which it is shown in Figs. 1, 2, 3 and 4 to its rearmost position, as shown in Fig. 7.

The initial portion of the rearward movement of the action-slide 19 as above described, will cause the surfaces of the cam-recess 27 in the enlarged rear portion 28 thereof, to coact with the operating-lug 26 of the breech-bolt 18, and effect the clockwise turning movement (as viewed from the front) of the said breech-bolt. The turning movement of the breech-bolt as just described will disengage the rear faces of its locking-lugs 20 and 21 from the locking-abutments 23 and 25 of the receiver 15, to thus unlock the breech-bolt.

Following the unlocking movement of the breech-bolt as just above described, the continued coaction of the surfaces of the cam-recess 27 of the action-slide 19 with the operating-lug 26 of the breech-bolt, will slide the said breech-bolt rearwardly to effect the extraction and ejection of the just-fired cartridge, in a manner well known in the art.

During the rearward travel of the action-slide 19, the left side of its cross-head 31 will engage with the releasing-surface 85 of the flexible timing-bar 72 to thus spring the forward end of the timing-bar outwardly. Ultimately the cross-head 31 will move rearwardly of the hook 84 so that the forward portion of the timing-bar may spring inwardly as shown in Fig. 7. It will be noted that when the parts are in the positions shown in Fig. 7, the latching-abutment 86 is in a position to be engaged by the left portion of the forward face of the crosshead 31 when the action-slide again moves forwardly.

As the breech-bolt 18 moves rearwardly as above described, it will rock the hammer 62 rearwardly and cause the lower rear portion of its arm 61 to engage with and cam the secondary-sear 51 rearwardly against the tension of its sear-spring 57, since at this time the marksman will be maintaining the trigger 53 in its "pulled" position, as is especially well shown in Fig. 8.

The downward swinging movement of the arm 61 of the hammer 62 past the upper end of the secondary-sear 51 as above described, will place the upwardly-facing cocking-abutment 60 on the said arm in a position slightly below the downwardly-facing cocking-abutment 59 of the secondary-sear 51, so that the said hammer 62 will be held in its cocked position when the breech-bolt 18 again moves forwardly.

After the breech-bolt 18 has moved rearwardly to the limit of its movement to effect the re-

cocking of the hammer 62, the action-slide 19 will start forwardly under the urge of the breech-closing spring 40 and will draw the said breech-bolt forwardly, to pick up a fresh cartridge from any suitable magazine in a manner common in the art.

As the action-slide 19 moves forwardly as above described, the left portion of its forward face of its crosshead 31 will engage with the latching-abutment 86 at the forward end of the timing-bar 72, with the effect of pulling the said timing-bar forwardly against the tension of the timing-spring 76 as is shown in Fig. 5.

As the breech-bolt 18 reaches the limit of its forward movement under the force supplied by the action-slide 19, the respective rear faces of the locking-lugs 20 and 21 of the said breech-bolt, will be brought into registry with the forwardly-facing locking-abutments 23 and 25 of the receiver 15. As soon as this registration occurs, the surfaces of the cam-recess 27 in the rear end of the action-slide 19, will cause the breech-bolt 18 to turn in a counterclockwise direction (as viewed from the front) to thus engage the locking-lugs 20 and 21 with the locking-abutments 23 and 25 respectively.

As the action-slide 19 approaches the limit of its forward movement, pulling with it the timing-bar 72, the inclined releasing-surface 85 of the said timing-bar will engage with the releasing-surface 87 of the cylinder-lug 36 (see Fig. 5) to flex the forward portion of the said timing-bar 72 outwardly. Ultimately, the forward portion of the timing-bar will be flexed outwardly sufficiently to completely disengage its rearwardly-facing latching-abutment 86 from the crosshead 31 of the action-slide, to thus permit the said timing-bar 72 to be snapped rearwardly by the action of the previously-compressed timing-spring 76. The release of the timing-bar 72 as just described will not take place, however, until after the breech-bolt 18 has been locked, as before described.

When the timing-bar 72 is snapped rearwardly by the timing-spring 76, its rear end will ultimately strike the forward face of the left arm 45 of the sear-actuating lever 44, to force the same rearwardly and thus cause the entire lever 44 to swing about its pivot-pin 48 against the tension of the breech-closing spring 40 which is thrusting rearwardly against the forward face of the right arm 43 all as shown in Fig. 6.

The swinging movement of the sear-actuating lever 44 as above described, will cause its depending tripping-finger 50 to swing the upper end of the secondary-sear 51 rearwardly. The rearward movement of the secondary-sear 51 as just described will retire its downwardly-facing cocking-abutment 59 out of the path of movement of the upwardly-facing cocking-abutment 60 of the hammer 62 and thus release the said hammer to forward swinging movement, to thus again effect the discharge of the firearm and the repetition of the cycle of operation above described until such time as the supply of cartridges is exhausted or until the marksman releases rearward draft upon the trigger 53.

Following the rocking of the sear-actuating lever 44 by the impact of the timing-bar 72, the said lever will swing back into its normal position (see Figs. 5 and 7) under the urge of the breech-closing spring 40 and against the relatively-weaker tension of the timing-spring 76.

When the marksman releases rearward draft upon the trigger 53, the sear-arm 61 thereof will

swing rearwardly and thus interpose its downwardly-facing cocking-abutment 66 in the path of movement of the upwardly-facing cocking-abutment 65, to thus restrain the hammer in its cocked position until such time as the hammer 53 is again intentionally pulled rearwardly.

The so-called "timing-bar" 72 requires a measurable period of time to move rearwardly when it is unhooked from the action-slide as above described, and this interval may be varied to meet various requirements for rates-of-fire by suitably proportioning any or both of the mass of the said timing-bar or its equivalent, and the tension of the timing-spring 76 or its equivalent.

Semiautomatic operation

When it is desired to have the firearm function as a semiautomatic firearm, the selector-lever 78 will be turned so that its finger-piece 79 projects rearwardly as indicated by broken lines in Figs. 3 and 4 instead of forwardly as indicated by full lines in the same figures. This turning movement of the selector-lever 78 will swing the eccentric-finger 81 at the lower end of its stem 77, outwardly to thus spring the forward end of the timing-bar 72 outwardly into the position in which it is shown in Fig. 13. In the position just referred to, the hook 84 at the front of the timing-bar 72 will be swung outwardly sufficiently so that its rearwardly-facing latching-abutment 86 will not be engaged by the crosshead 31 of the action-slide 19 as the same reciprocates.

Now when the firearm is discharged, the action-slide 19 will be driven rearwardly and the breech-bolt will be unlocked and moved rearwardly in a manner corresponding to that described in connection with the full automatic operation of the firearm. The hammer 62 will also be swung rearwardly and in the event—as is usually the case—that the marksman has not had time to release rearward draft upon the trigger 53, the said hammer 62 will be caught and held in its cocked position by the secondary-sear 51 as illustrated in Fig. 8.

As the action-slide moves, the timing-bar 72 will be in no way affected, nor will the sear-actuating lever 44, so that there will be no automatic discharge of the firearm.

As soon as the marksman releases rearward draft upon the trigger 53, the secondary-sear 51 will swing rearwardly to disengage itself from the hammer 62 but not before the sear-arm 67 of the trigger 53 has moved rearwardly into a position wherein its downwardly-facing cocking-abutment 66 is interposed in the path of movement of the upwardly-facing cocking-abutment 65 of the hammer 62. When the trigger has been fully released, the hammer 62 will swing a short distance forwardly and upwardly until its cocking-abutment 65 is engaged with the cocking-abutment 66 of the sear-arm 67.

From the foregoing it will be seen that when the firearm is set for semiautomatic fire, the mere holding-back of the trigger 53 will not cause a repeat discharge of the firearm, since the sear-actuating lever 44 has not been moved and hence the trigger must be first released to disengage the secondary-sear 51 from the hammer 62 and must then again be pulled, to, in turn, disengage the sear-arm 67 of the said trigger from the hammer 62.

It is to be noted that while, in the particular embodiment of the invention as shown, the timing-bar is latched to the action-slide, the said timing-bar is in effect latched to the breech-

bolt through the intermediary of the said action-slide since the latter may properly be viewed as part of the breech-bolt assembly.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An automatic firearm including in combination: a receiver; a breech-bolt movable in the said receiver; an action-slide movable lengthwise of the firearm-structure and operatively connected to the said breech-bolt for moving the same in the said receiver, the said action-slide having a lost-motion connection with the breech-bolt and provided with a forwardly-facing latching-abutment; a firing-member for effecting the discharge of the firearm; a sear for releasably holding the said firing-member in a cocked position; a timing-member mounted for reciprocation lengthwise of the firearm-structure and carrying a latching-portion yieldable in a direction transverse of the firearm-structure, the said latching-portion having a rearwardly-facing latching-abutment releasably engageable with the forwardly-facing latching-abutment of the said action-slide; spring-means urging the said timing-member rearwardly into a retired position; the said timing-member being constructed and arranged to retire the said sear when the latching abutment of the said timing-member is disengaged from the latching-abutment of said action-slide and the timing-member retires under the urge of the said spring-means; and releasing-means constructed and arranged to automatically move the transversely-yielding latching-portion of the said timing-member to disengage its latching-abutment from the latching-abutment of the said action-slide when the latter has moved the said breech-bolt substantially into its breech-closing position.

2. An automatic firearm including in combination: a receiver; a breech-bolt movable in the said receiver; an action-slide operatively connected to the said breech-bolt for moving the same in the said receiver and having a lost-motion connection therewith; a breech-closing spring urging the said breech-bolt into its breech-closing position; a firing-member for effecting the discharge of the firearm; a sear for releasably holding the said firing-member in a cocked position; a sear-actuating lever operatively associated with the said sear and with the said breech-closing spring and moved by the latter in a direction counter to the movement imparted to it by the hereinafter-mentioned timing-member; a timing-member having a latching-portion releasably connectible to the said action-slide for moving the timing-member therewith during the movement of the said breech-bolt from its retired position to its breech-closing position; spring-means urging the said timing-member in a direction opposite to that in which it is moved by the breech-closing movement of the said action-slide; the said timing-member being constructed and arranged to swing the said sear-actuating lever against the tension of the said breech-closing spring to cause the said lever to retire the said sear when the latching-portion of the said timing-member is disengaged

from the said action-slide and it retires under the urge of the said spring-means; and releasing-means constructed and arranged to automatically disconnect the latching-portion of the said timing-member from the said action-slide when the latter has moved the said breech-bolt substantially into its breech-closing position.

3. An automatic firearm including in combination: a receiver; a breech-bolt movable in the said receiver; an action-slide operatively connected to the said breech-bolt for moving the same in the said receiver and having a lost-motion connection therewith; a breech-closing spring urging the said breech-bolt into its breech-closing position; a firing-member for effecting the discharge of the firearm; a sear for releasably holding the said firing-member in a cocked position; a sear-actuating lever operatively associated with the said sear and with the said breech-closing spring and moved by the latter in a direction counter to the movement imparted to it by the hereinafter-mentioned timing-member; a timing-member having a latching-portion releasably connectible to the said action-slide for moving the timing-member therewith during the movement of the said breech-bolt from its retired position to its breech-closing position; manually-operable selector-means constructed and arranged to selectively render the latching-portion of the said timing-member operative or inoperative; spring-means urging the said timing-member in a direction opposite to that in which it is moved by the breech-closing movement of the said action-slide; the said timing-member being constructed and arranged to swing the said sear-actuating lever against the tension of the said breech-closing spring to cause the said lever to retire the said sear when the latching-portion of the said timing-member is disengaged from the said action-slide and it retires under the urge of the said spring-means; and releasing-means constructed and arranged to automatically disconnect the latching-portion of the said timing-member from the said action-slide when the latter has moved the said breech-bolt substantially into its breech-closing position.

4. An automatic firearm including in combination: a receiver; a breech-bolt movable in the said receiver; an action-slide movable lengthwise of the firearm-structure and operatively connected to the said breech-bolt for moving the same in the said receiver, the said action-slide having a lost-motion connection with the breech-bolt; a breech-closing spring urging the said breech-bolt into its breech-closing position; a firing-member for effecting the discharge of the firearm; a sear for releasably holding the said firing-member in a cocked position; a sear-actuating lever operatively associated with the said sear and with the said breech-closing spring and moved by the latter in a direction counter to the movement imparted to it by the hereinafter-mentioned timing-member; a timing-member mounted for reciprocation lengthwise of the firearm-structure and having a latching-portion releasably connectible to the said action-slide for moving the timing-member forwardly therewith during the forward movement of the said action-slide; spring-means urging the said timing-member rearwardly for engagement with the said sear-actuating lever; the said timing-member being constructed and arranged to swing the said sear-actuating lever against the tension of the said breech-closing spring to cause the said lever to retire the said sear when the latching-portion

of the said timing-member is disengaged from the said action-slide and the timing-member retires under the urge of the said spring-means; and releasing-means constructed and arranged to automatically disconnect the latching-portion of the said timing-member from the said action-slide when the latter has moved the said breech-bolt substantially into its breech-closing position.

5. An automatic firearm including in combination: a receiver; a breech-bolt movable in the said receiver; an action-slide movable lengthwise of the firearm-structure and operatively connected to the said breech-bolt for moving the same in the said receiver, the said action-slide having a lost-motion connection with the breech-bolt and provided with a forwardly-facing latching-abutment; a firing-member for effecting the discharge of the firearm; a sear for releasably holding the said firing-member in a cocked position; a timing-member mounted for reciprocation lengthwise of the firearm-structure and having a flexible forward portion provided with a rearwardly-facing latching-abutment releasably engageable with the forwardly-facing latching-abutment of the said action-slide; spring-means urging the said timing-member rearwardly; the said timing-member being constructed and arranged to effect the retirement of the said sear when its latching-abutment is disengaged from the latching-abutment of the action-slide and the timing-member moves rearwardly under the urge of the said spring-means; and releasing-means constructed and arranged to automatically flex the forward portion of the timing-member and disengage the latching-abutment of the timing-member from the latching-abutment of the action-slide when the latter has moved the said breech-bolt substantially into its breech-closing position.

6. An automatic firearm including in combination: a receiver; a breech-bolt movable in the said receiver; an action-slide movable lengthwise of the firearm-structure adjacent one side thereof and operatively connected to the said breech-bolt for moving the same in the said receiver, the said action-slide having a lost-motion connection with the breech-bolt; a firing-member for effecting the discharge of the firearm; a sear for releasably holding the said firing-member in a cocked position; a sear-actuating lever operatively associated with the said sear and mounted for turning movement about a substantially-vertical axis; a longitudinal breech-closing spring having its forward portion thrusting forwardly upon the said action-slide and having its rear end thrusting rearwardly upon the adjacent end of the said sear-actuating lever; a timing-member mounted for reciprocation lengthwise of the firearm-structure adjacent the side thereof opposite from the said action-slide and having a latching-portion releasably connectible to the said action-slide for moving the timing-member forwardly therewith during the forward movement of the said action-slide; spring-means urging the said timing-member rearwardly into engagement with the end of the said sear-actuating lever opposite the end thereof engaged by the said breech-closing spring; the said timing-member being constructed and arranged to engage with and swing the said sear-actuating lever against the tension of the said breech-closing spring to cause the said sear-actuating lever to retire the said sear when the latching-portion of the said timing-member is disengaged from the said action-slide and the timing-member retires under the urge of the said spring-means; and releasing-means constructed

and arranged to automatically disconnect the latching-portion of the said timing-member from the said action-slide when the latter has moved the said breech-bolt substantially into its breech-closing position.

DAVID M. WILLIAMS.
